US00D988299S

(12) **United States Design Patent** (10) **Patent No.:** **US D988,299 S**
(45) **Date of Patent:** **** Jun. 6, 2023**

(54) **CELLULAR MODULE**

(71) Applicant: **Telit Cinterion Deutschland GmbH**,
Munich (DE)

(72) Inventor: **Annette Horn**, Munich (DE)

(**) Term: **15 Years**

(21) Appl. No.: **35/513,245**

(22) Filed: **Jun. 18, 2021**

(80) **Hague Agreement Data**

Int. Filing Date: **Jun. 18, 2021**

Int. Reg. No.: **DM/215215**

Int. Reg. Date: **Jun. 18, 2021**

Int. Reg. Pub. Date: **Dec. 24, 2021**

(51) **LOC (14) Cl.** **14-03**

(52) **U.S. Cl.**

USPC **D14/230**

(58) **Field of Classification Search**

USPC D14/230, 231–239, 356–359, 435–437,
D14/155; D10/104.1, 106.9; D13/147,
D13/182

Assistant Examiner — Samina Vieth

(57) **CLAIM**

The ornamental design for a cellular module, as shown and described.

DESCRIPTION

1. Cellular module
2. Cellular module
3. Cellular module
4. Cellular module
5. Cellular module
6. Cellular module

1.1 : Bottom

1.2 : Top

1.3 : Right

1.4 : Left

1.5 : Front

1.6 : Back

1.7 : Perspective

2.1 : Bottom

2.2 : Top

2.3 : Right

2.4 : Left

2.5 : Front

2.6 : Back

2.7 : Perspective

3.1 : Bottom

3.2 : Top

3.3 : Right

3.4 : Left

3.5 : Front

3.6 : Back

3.7 : Perspective

4.1 : Bottom

4.2 : Top

4.3 : Right

4.4 : Left

4.5 : Front

4.6 : Back

4.7 : Perspective

(Continued)

5.1 : Bottom
5.2 : Top
5.3 : Right
5.4 : Left
5.5 : Front
5.6 : Back
5.7 : Perspective
6.1 : Bottom
6.2 : Top
6.3 : Right
6.4 : Left
6.5 : Front
6.6 : Back
6.7 : Perspective

Designs No. 1 and 2 show versions of a cellular module with respectively 0 and 3 pads arrangements; Designs No. 3 and No. 4 show versions of a cellular module with respectively 5 and 6 pads arrangements; Designs No. 5 and No. 6 show versions of a cellular module with respectively 0 and 1 pads arrangements. The broken lines illustrate portions of the article, and form no part of the claimed design.

1 Claim, 42 Drawing Sheets

(58) Field of Classification Search

CPC H01Q 1/241; H01Q 1/243; H04B 1/38
